(57) CLAIM

The ornamental design for an inflatable kids lounger chair, as shown and described.

DESCRIPTION

FIG. 1 is an upper front perspective of an inflatable kids lounger chair embodying my design;

FIG. 2 is a front elevation of the inflatable kids lounger chair shown in FIG. 1;

FIG. 3 is a side elevation of the inflatable kids lounger chair shown in FIGS. 1 and 2, with the opposite side elevation being substantially identical thereof;

FIG. 4 is a rear elevation of the inflatable kids lounger chair shown in FIGS. 1-3;

FIG. 5 is a top view of the inflatable kids lounger chair shown in FIGS. 1-4;

FIG. 6 is a bottom view of the inflatable kids lounger chair shown in FIGS. 1-5; and,

FIG. 7 is a fragmentary front perspective of the inflatable kids lounger chair shown in FIGS. 1-6.
